METHOD OF SEPARATING SHOES FROM
LASTSJohn B. Hadaway, Swampscott, Mass., assignor
to United Shoe Machinery Corporation, Pater-
son, N. J., a corporation of New Jersey

Application August 29, 1934, Serial No. 741,951

4 Claims. (Cl. 12—142)

This invention relates to the art of separating shoes from lasts and is herein disclosed with reference to an improved method involving the application of pressure against the interior of a shoe on a last to separate or to facilitate separation of the shoe from the last. The application for United States Letters Patent, Serial No. 706,087, filed January 10, 1934, in the name of Elmer Grush, discloses a method of utilizing pressure within a shoe to separate the shoe from the last. The present invention is similar to that disclosed in the above-mentioned application of Grush in so far as both contemplate the use of pneumatic pressure.

It is an object of the present invention to provide an improved method of separating a shoe from a last.

In accordance with a feature of the invention, pressure is applied in diverging directions against a plurality of localities simultaneously on the interior of the rear portion of a shoe upper to expand the rear portion of the shoe and thereby to facilitate its removal from the last. The shoe expanding force is obtained by the use of air under pressure which is introduced into the rear portion of a shoe, preferably through a tubular last pin, and thence through diverging passages in the last which direct the compressed air against the shoe upper. The expanded rear portion of the shoe may then easily be removed from the last by hand or by a machine which applies frictional force against the exterior of the shoe. In either case, the force operating upon the exterior of the shoe may be assisted by air pressure directed through one or more passages in the last against the interior of the shoe bottom.

Referring now to the accompanying drawings,—

Fig. 1 is a view in side elevation of a lasted shoe and a machine suitable for use in carrying out the improved method;

Fig. 2 is a plan view of the rear end of a last shown in Fig. 1;

Fig. 3 is an elevational view of the last pin shown in Fig. 1;

Fig. 4 is a sectional view taken on the line IV—IV of Fig. 1; and—

Fig. 5 is a view in side elevation illustrating the use of a machine different from that shown in Fig. 1 but operating in accordance with the improved method.

In carrying out the improved method, a last L within a shoe S is mounted upon an upstanding last pin 10. The illustrated last L, as shown in Fig. 1, is of the hinged type, consisting of a

forward portion and a rear portion which are connected by a hinge 12. The rear portion of the last L has formed in it the usual thimble hole which is lined with a metallic ferrule 14 for receiving the last pin 10. The last pin 10 is carried by the upper end of a standard 16 which rises from a base 18 resting upon the floor. The standard 16 may receive additional support from a work table 18.

The last pin 10 is tubular and communicates 10 (as shown in Fig. 1) with a conduit 20 within the standard 16, the lower end of the conduit 20 being connected to the outlet side of a valve 22 (Figs. 1 and 4). The inlet side of the valve 22 communicates with a conduit 24 which is adapted 15 to be connected to a supply of air under pressure. Within the valve 22 is a rotary valve plug 26 having formed in it a port 28 (Fig. 4) which, upon rotation of the plug 26, opens and closes communication between the conduits 24 and 20. 20 Extending from the valve plug 26 is a crank 30 which is connected by a link 32 to a treadle 34 fulcrumed at 36 upon the base 18. The treadle 34 is normally held upwardly by a spring 38 in which position the plug 26 closes communication be- 25 tween the conduits 24 and 20. Upon depression of the treadle 34 the valve plug 26 is rotated to a position wherein the port 28 connects the conduits 24 and 20. This open position of the valve 22 is determined by a stop 40 which limits de- 30 pression of the treadle 34.

The last L has formed in its rear portion a plurality of diverging ducts or passages 42 each of which communicates at one end, through a suitable opening in the ferrule 14, with the interior of the thimble hole of the last. The opposite ends of the ducts 42 are directed against the interior of the upper of the shoe S at a substantial distance from both the last bottom and the top of the last. While the ducts 42 are shown 40 in the illustrated last as all opening against the interior of the shoe at the same level, it may in certain cases be advantageous to stagger the openings of the ducts or to provide an additional set of ducts at a different level. In addition to 45 the ducts 42 there is formed also in the last L a pair of ducts 44 which communicate with the interior of the thimble hole and which are directed against the interior of the rear portion of the shoe bottom. Except for the above de- 50 scribed ducts the last L is of normal shape and is adapted to enter into snug engagement with the interior of the shoe S.

After the lasted shoe has been mounted upon the last pin 10, as shown in Fig. 1, air is admitted 55

into the interior of the shoe by depressing the treadle 34. The air pressure is thus applied in diverging directions against a plurality of localities simultaneously on the interior of the rear end of the shoe upper, the effect of which is to produce momentarily a considerable expansion of the rear end of the shoe and to urge the interior of the rear end of the shoe away from the last L. It is important that the air pressure be admitted simultaneously in order that it may develop its full expanding effect at all of the localities at which this effect is desired before any of the air has an opportunity to escape from between the last and the shoe. Because of the snug fit between the last and the shoe, the air will not escape immediately, but will spread out into a thin film between the last and the shoe. This film not only urges the shoe away from the last but serves also as a lubricant. The operator may then readily lift the rear end portion of the shoe by hand from the last L. In the case of a hinged last, such as the last L, this operation may conveniently be performed with one hand while the other hand bears down upon the forward portion of the shoe bottom to break the last L. Such breaking of the last tends to tilt the shoe and materially assists in removing the rear portion of the shoe from the last. However, whether a hinged or a block or a one-piece last be employed, the air pressure is effective in facilitating the removal of the rear end of the shoe from the last. The removal of the rear end of the shoe is assisted by air pressure which is directed against the shoe bottom through the ducts 44. The removal of the forepart of the shoe from the last may readily be accomplished by hand.

Fig. 5 shows how the improved method may be carried out in connection with the use of a machine of the type disclosed in United States Letters Patent No. 1,820,952, granted Sept. 1, 1931, upon the application of John M. Whelton and Arthur F. Pym. This machine is provided with a power-driven friction roll 46 carried by a shaft 48 journaled in the upper portion of a frame 50. The last pin 10 is carried in the upper portion of a lever 52 which replaces the standard 16 of the device shown in Fig. 1. The lower end of the lever 52 is fulcrumed upon trunnion pins 54 in such a manner as to enable the rear end of the shoe S to swing toward the roll 46. The swinging of the lever 52 is effected by a treadle 56. The machine illustrated in Fig. 5 as so far described is substantially like that disclosed in the above-mentioned Letters Patent No. 1,820,952 to which reference may be had for a more detailed disclosure. The last pin 10 is secured upon the upper end of a tubular rod 58 which is slidably mounted in the lever 52 and which may be raised and lowered for purposes of adjustment by a mechanism comprising a knurled head 60 and which is in all respects similar to the mechanism for adjusting the last pin of the machine disclosed in Letters Patent No. 1,820,952, above mentioned. The lower end of the tubular rod 58 is connected by a flexible conduit 62 to the outlet end of a valve 64 mounted upon the lever 52 and having a stem 66 which opens the valve when pressed inwardly. The inlet end of the valve 64 is connected by a flexible conduit 68 to a hand-operated valve 70 which in turn is connected by a pipe 72 to a sup-

ply of air under pressure. Mounted upon the frame 50 is an adjustable abutment 74, which, as the lever 52 swings inwardly, is engaged by the valve stem 66 to open the valve. When the lever 52 moves away from the abutment 72 the stem 66 is urged outwardly and the valve is closed by a spring with which such valves are ordinarily provided.

In carrying out the method with the use of the machine illustrated in Fig. 5, the last L is first placed upon the last pin 10 and the treadle 56 is then depressed, swinging the lever 52 inwardly and bringing the rear end portion of the shoe into engagement with the roll 46. As the lever 52 swings inwardly the valve 64 is opened and air is admitted into the rear end portion of the shoe, expanding that portion of the shoe in the same manner as has already been described with reference to the apparatus shown in Fig. 1. The same inward swinging movement of the lever 52 brings the rear end of the shoe upper into engagement with the roll 46 which is driven in a direction to raise the rear end of the shoe from the last. The operator may at the same time press upon the forepart of the sole of the shoe to break the last. The forepart of the shoe may then be pulled from the forepart of the last.

Having described my invention, what I claim as new and desire to secure by Letters Patent of the United States is:

1. That improvement in methods of separating shoes from lasts which consists in the step of applying pressure in diverging directions simultaneously against a plurality of localities on the interior of the rear portion of a shoe upper to expand the rear portion of the shoe relatively to a last upon which the shoe is mounted, and in applying pressure against the interior of the rear portion of the shoe bottom to separate the rear portion of the shoe from the last.

2. That improvement in methods of separating shoes from lasts which consists in forcing air under pressure in diverging directions simultaneously against a plurality of localities on the interior of the rear portion of a shoe upper to expand the rear portion of the shoe relatively to a last upon which the shoe is mounted, and in forcing air under pressure against the interior of the rear portion of the shoe bottom to separate the rear portion of the shoe from the last.

3. A method of separating a shoe from a last which consists in supporting the last upon a last pin, applying pressure in diverging directions simultaneously against a plurality of localities on the interior of the rear portion of the shoe upper to expand the rear portion of the shoe, and in applying a frictional force against the exterior of the rear portion of the shoe in a direction to separate the rear portion of the shoe from the last.

4. A method of separating a shoe from a hinged last which consists in mounting the last upon a last pin, applying pressure in diverging directions simultaneously against a plurality of localities on the interior of the rear portion of the shoe upper to expand the rear portion of the shoe, and in applying pressure against the tread surface of the forward portion of the shoe sole to break the last and thereby to separate the rear portion of the shoe from the last.
